UNITED STATES PATENT OFFICE.

BENGIMAN FREEDMAN, OF CONEY ISLAND, NEW YORK.

LOCK.

1,337,511.

Specification of Letters Patent. Patented Apr. 20, 1920.

Application filed May 28, 1919. Serial No. 300,415.

To all whom it may concern:

Be it known that I, BENGIMAN FREEDMAN, a citizen of Russia, residing at Coney Island, Kings county, State of New York, 5 have invented certain new and useful Improvements in Locks, of which the following is a full, clear, and exact description.

This invention relates to an improvement in locks of the variety used for doors, etc. 10 One of the objects of my invention is to provide a lock mechanism a part of which is removable, that is to say, one of the knobs thereof which acts to move the bolts of the lock. A further object is to provide a lock 15 mechanism having a plurality of bolts and means to actuate the bolts in unison to release the door or other similar element to which the mechanism may be attached. Other features of improvement will be set 20 forth in the following description of the device, reference being had to the accompanying drawing, wherein:

Figure 1 is a sectional face view of the lock, the section being taken on a line 1—1 25 in Fig. 2;

Fig. 2 is a longitudinal sectional view, the section being taken on a line 2—2 in Fig. 1;

Fig. 3 is an end view looking from the left in Fig. 1;

Fig. 4 is an enlarged fragmentary sectional view, the section being taken on a line 4—4 in Fig. 1;

Fig. 5 is an enlarged sectional detail view, the section being taken on a line 5—5 in 35 Fig. 1;

Fig. 6 is a top plan view illustrating the lock, its keeper and a portion of a door and door-casing; and

Fig. 7 is an enlarged sectional view, the 40 section being taken on a line 7—7 in Fig. 6, the bolts being shown in elevation.

My improved lock consists of a casing 8, which contains the main bolt 9, supplemental bolts or carriers 10 and 11, and the 45 operating mechanism for said bolts or carriers. The bolt 9 is arranged to enter an opening 12 in a keeper 13, while the bolts or carriers 10 and 11 each carry means to engage openings 14 and 15 in the ends of 50 said keeper 13. The bolts or carriers 10 and 11 are each provided with a yieldable nose-piece 16 mounted in a socket 17 in said

bolts or carriers 10 and 11, a spring 18 being provided to normally maintain the nose-pieces in extended position. The bolts 10 55 and 11 are arranged to move longitudinally of the casing 8, in the direction of the arrows 19, and are provided with slots 20 to engage projections 21 carried by the casing 8. Each bolt 10 and 11 carries male cam-members 22 to engage female cam-recesses 23 formed in oscillatable plates 24 and 25. The plates 24 and 25 are pivotally connected to the casing by means of a thimble 26 which is also rotatably mounted on said 60 casing, said thimble having a flange 27 at one end thereof and a collar 28 at the opposite end thereof, as illustrated in Fig. 4. The plates 24 and 25 are arranged to be actuated independently of each other, one 65 (plate 24) being actuated exteriorly of a door 29 for instance, and the plate 25 interiorly of the said door. The plate 25 is oscillated by means of a knob 30, having a square end 31 (in this instance) to engage 70 a squared socket 32 in the thimble 26. The thimble 26 is also provided with a cylindrical opening 33 engaged by a round seat 34 carried by a shank 35, which is connected at its outer end to a lock mechanism 80 36 illustrated in a general way in Fig. 2. The shank 35 carries arms 37, having pins 38 to engage beadings 39 carried by the main bolt 9. The bolt 9 also carries other beadings 40 to be engaged by pins 41 carried 85 by arms 42 extending from the flange 27 of the rotatable thimble 26. Shank 35 is further provided with another arm 43, having a pin 44 to engage a slot 45^a in the plate 24. 90

The main bolt 9 is maintained in normal extended position by springs 45 which surround guide-pins 46 supported at their inner end by a bracket 47. At its outer end, bolt 9 is supported by the walls of the opening 48 in the casing 8. To permit of the movement of the tongues 10 and 11, the casing is provided with elongated openings 48^a. The knob 30 is removably mounted in the thimble 26 in order that it can be taken out 95 to prevent the bolts from being operated interiorly of the door. The bolt 9 and nose-pieces 16 will automatically move inwardly due to the inclined walls 49 and 50, 100

respectively, when the door is closed, and will be returned to normal position by the springs 45 and 18, respectively, after said bolt and nose-pieces have alined with their 5 respective openings in the keeper 13. The door will now be locked and cannot be opened unless a key is employed to rotate shank 35 or the knob 30 to rotate plate 25. When the knob 30 is rotated, the bolt 9 will 10 be moved inwardly against the tension of the springs 45, as pins 41 bear against the beadings 40 on bolt 9. The plate 25 will also be rotated, as said plate is fastened to the rotatable thimble 26, in this instance, by 15 a spline 51. When plate 25 is rotated, the bolts 10 and 11 will be moved in the direction of the arrows 19, against the tension of the leaf-springs 52 by the action of the cams 22 and cam-recesses 23. This movement will be sufficient to free the nose-pieces 20 from the keeper, and bolt 9 will also be moved in sufficiently to clear said nose-pieces. The described movement of the said bolts will permit the door to be opened. 25 Should a key be used to operate the lock 36, the shank 35 will be rotated, causing pins 38 on arms 37 to move the bolt 9 inwardly and pin 44 on arm 43 to rotate plate 24, as said pin engages the slot 45^a in said plate. 30 It will be apparent that the bolts are operated by the actuation of either the knob 30 or the lock mechanism 36. The socket 32 in the thimble may be of any desired shape, but the projection 31 on knob 30 must be 35 of a corresponding shape.

One of the advantages of my improved mechanism is that the door can not be opened from the inside without the use of the knob and if the knob 30 should be removed, the door can not be opened from the inside. The key lock mechanism 36 will 40 be preferably of the cylinder variety.

By means of my improved lock mechanism, a door can not be opened from the inside should the knob 30 be removed; hence should a thief enter a room, through a window opening, he could not pass out of the room through the door, as the lock mechanism could not be operated. The door, 45 however, could be opened from the outside by means of a proper key.

Having described my invention, what I claim is:—

1. In a lock, a bolt arranged for a reciprocating movement, a plurality of slidably mounted bolts, a yieldable nose carried by each slidable bolt, means to actuate said slidable bolts, and an oscillatable shank arranged to actuate the slidable bolt operating means and also the reciprocatable bolt. 55
2. In a lock, a casing, a rotatable thimble carried thereby, a plate secured to said thimble, a second plate loosely mounted upon said thimble, bolts engaged by said plates, a knob 60

removably secured to said thimble to actuate the plate secured thereto, and a key operated mechanism to operate the other of said plates. 65

3. In a lock, a casing, a rotatable thimble carried thereby, a plate secured to said thimble having cam-recesses therein, a second plate loosely mounted on said thimble having cam slots therein, bolts having cams engaging said recesses and means to actuate said plates independently of each other. 70

4. In a lock, a reciprocable main bolt, a beading on opposite surfaces of said bolt, a supplemental tongue adjacent the main bolt, a plurality of independently acting devices to operate the supplemental bolt, a shank, arms carried thereby to engage one of the beadings on the main bolt and one of the supplemental tongue actuating devices, and means engaging the other beading on the main bolt and arranged to actuate the other supplemental bolt actuating device, without operating said shank. 75

5. In a lock, the combination of a keeper having an opening intermediate its ends, and an opening in each end, a casing, a bolt carried thereby to engage the opening intermediate the ends of the keeper, bolts to engage the openings at the ends of said keeper, slidably supported by said casing and arranged for movement longitudinally thereof, a yieldably supported nose carried by each of the bolts last named, and arranged to engage a corresponding opening at the ends of the keeper, a plurality of actuating devices for said bolts, and means to operate said actuating devices independently of each other. 90

6. In a lock, a casing, a bolt carried thereby arranged for reciprocation, carriers slidably supported by said casing, a yieldable nose carried by each carrier, means to actuate said bolt, and means to actuate the slidable carriers. 105

7. In a lock, a casing, a bolt carried thereby arranged for reciprocation, carriers slidably supported by said casing, a yieldable nose carried by each carrier, an oscillatable plate to actuate the carriers, and means to operate said plate. 110

8. In a lock, a casing, a bolt carried thereby arranged for reciprocation, carriers slidably supported by said casing, a yieldable nose carried by each carrier, and means common to the bolt and carrier to operate the same. 115

9. In a lock, a casing, a bolt carried thereby, a beading carried by said bolt at its inner end, a supplemental bolt adjacent thereto, a plate to actuate said supplemental bolt having a slot, an oscillatable shank, an arm carried thereby to engage said beading, and an arm also carried by the said shank to engage said slot, all arranged so that the 120 125

said bolts will be operated when said shank is actuated.

10. In a lock, a key operated mechanism, a bolt operable by the key operated mechanism, and a knob operated mechanism arranged to operate said bolt independently of the key operated mechanism, said knob being normally arranged for disconnection

from its coöperating bolt operating mechanism. ¹⁰

Signed at New York city, N. Y., this 27 day of May, 1919.

BENGIMAN FREEDMAN.
